Atty.

UNITED STATES PATENT OFFICE.

EARL G. WATROUS, OF CHICAGO, ILLINOIS.

CARBURETOR HEATER.

1,402,461.

Specification of Letters Patent. Patented Jan. 3, 1922.

Application filed March 17, 1919. Serial No. 283,197.

To all whom it may concern:

Be it known that I, EARL G. WATROUS, a citizen of the United States, residing at Chicago, in the county of Cook and State of Illinois, have invented certain new and useful Improvements in Carburetor Heaters, of which the following is a specification.

The necessity or desirability of raising the temperature of the gasoline or fuel used for internal combustion engines during cold weather is well understood. The present invention relates to a device or apparatus, whereby the fuel may be heated in the carburetor in a particularly direct and effective manner by means of current from the storage batteries such as are commonly used in connection with automobiles and other power plants.

The object of this invention is to provide an electric heater for heating the fuel in a carburetor in a direct manner so as to avoid all possible loss of heat units; to provide an electric heater for carburetors, which is of simple construction and which may be readily applied; and in general to provide such an improved heater as will be described more fully hereinafter.

In the accompanying drawings illustrating this invention:

Fig. 1 is a side view of a carburetor with parts broken away to show the interior construction and with the heater applied thereto, parts being also shown diagrammatically;

Fig. 2 is a section taken on the line 2—2 of Fig. 1;

Fig. 3 is a side view showing a modified form of heater; and,

Fig. 4 is a plan view of the device shown in Fig. 3.

This invention is particularly adapted to be used in connection with motor vehicles, such vehicles now being commonly supplied with storage batteries for the starting and lighting systems. These batteries however are of somewhat limited capacity and it is not practical to use a considerable amount of current therefrom for the purpose of heating the gasoline. I have found that the gasoline may be heated with the smallest amount of loss of heat units, by immersing the electric heating element directly in the liquid and I utilize this in my improved heater. This arrangement is particularly useful for heating the gasoline during cold weather in order that the engine will start

readily, and I have found that the gasoline may be heated to a sufficiently high temperature for this purpose in a comparatively few seconds and without undue drain on the battery.

As shown in the drawings, 5 indicates the bowl of the carburetor which may be of any ordinary or preferred form of construction. This carburetor is provided with the usual float 6 and needle valve 7 having a valve seat 8. One end 9 of the heating element 10 is wound around or secured to the valve seat 8 so as to provide a contact or electric connection. The other end 11 is secured to a bolt 12 which extends down through a hole 13 in the bottom of the bowl 5. The bolt is insulated from the bowl by means of insulation 14. The heating element 10 preferably comprises a wire formed of suitable resisting material such as German silver or other composition. This element is insulated from the bowl by means of an insulating disk 15, formed of mica or other suitable material.

The bolt 12 is connected by a wire 16 with one terminal of the battery 17. The other terminal is grounded by means of a wire 18 connected to the supply pipe 19 or other suitable place for grounding. A switch 20 is provided at any convenient point for opening and closing the circuit. When this switch is closed, the current passes from the battery through the wire 16 and bolt 12 to the heating element 10 and then to ground or back to the battery. The heating element becomes quickly heated and will heat the fuel in the bowl very rapidly as the fuel is directly exposed to the wire and is free to circulate around the heating element which preferably covers a considerable area of the bottom. It will also be noted that this attachment may be applied to the carburetor without changing the same, other than by providing a hole for the bolt 12.

In some instances it may be desired to install the heater without making a hole through the bowl and in some instances it is desirable to provide a complete circuit for the heater instead of grounding one terminal of the same. The arrangement shown in Figs. 3 and 4 is adapted to fulfill these conditions. In this instance, a disk 21 of insulating material is provided to set in the bottom of the bowl. Insulated wires 22 and 23 are secured to the disk by means of fasteners 24 and have upwardly extending

branches 25 and 26 which may pass up through a suitable opening in the cover of the carburetor. These wires are covered with insulating material which will not be affected by the gasoline. The heating element 27 is connected to the ends of the wires 22 and 23 as shown in Fig. 4. The upper branches of the wires are connected to the battery in any well known manner, so that neither terminal of the heating element is grounded. The operation of this form is of course substantially the same as that just described.

It will be seen from this description, that I provide an electric heater which may be readily installed and which will be particularly efficient in operation, but it will be noted that changes may be made in order to adapt the same to other forms of carburetors and therefore I do not wish to be limited to the exact construction herein shown and described.

What I claim and desire to secure by Letters Patent is:

25 1. An electric heater for carburetors, comprising a heating element formed of a single bare wire adapted to be inserted in the fuel in the carburetor bowl, means for insulating the wire from the bowl, conductors 30 permanently connected to the ends of the heating element within the bowl, and means for supplying current to the conductors.

2. A heater for carburetors, comprising

a plate of insulating material, two insulated wires connected to said plate and having 35 upwardly extending branches, a heating element having its terminals connected to the ends of said wires adjacent to the plate, and means for connecting the upwardly extending branches to a source of electricity. 40

3. A heater for carburetors, comprising a plate of insulating material adapted to be immersed in the fluid in a carburetor, a bare wire heating element mounted on said plate, and insulated wire connections leading from 45 said heating element.

4. The combination with the bowl of a carburetor, of a bare resistance element arranged in the carburetor below the fuel level, means for insulating the resistance element 50 from the carburetor, and insulated conductor wires connected to the resistance element and passing out of the carburetor at a point above the fuel level.

5. A heater attachment for carburetors, comprising a disc of insulating material adapted to fit freely in the bowl of the carburetor, a heating element secured to said disc, insulated wires connected with the ends of said element and also secured to said disc, 55 said wires being adapted to project upwardly beyond the fuel level in the carburetor when the device is inserted in the bottom of the bowl. 60

EARL G. WATROUS.
